Attorney.

UNITED STATES PATENT OFFICE

2,082,747

ADJUSTABLE CRAVAT HOLDER

Edward L. Anderson, Attleboro, Mass., assignor
to Ripley and Gowen Company, Inc., Attle-
boro, Mass.

Application September 29, 1936, Serial No. 103,201

3 Claims. (Cl. 24—49)

This invention relates to a cravat holder and more particularly to a structure embodying means for adjusting the cravat holding means, and it consists in the constructions, arrangements and combinations herein described and claimed.

It is the cardinal purpose of the invention to provide a simple yet effective adjusting means whereby cravats of varying widths may be accommodated and still maintain the symmetrical appearance of the holder and particularly the ornament ordinarily suspended from the flexible member of the holder.

It is a further object of the invention to provide a cravat holder having an adjustable feature which is simple and inexpensive in construction and assembly.

Additional objects, advantages and features of invention will be apparent from the following description, considered in conjunction with the accompanying drawing wherein

Figure 1 is a plan view of the holder illustrating its application to a cravat.

Figure 2 is a top edge view of the holder.

Figure 3 is a longitudinal sectional view thereof.

Figure 4 is a longitudinal vertical sectional view, illustrating one of the anchorage members for the flexible chain in extended position.

Figure 5 is a rear elevation partly in section.

Figure 6 is a detail perspective view of one of the anchorage members.

Figure 7 is an enlarged cross section on the line 7—7 of Figure 2.

There is illustrated, generally, a cravat holder 10, which comprises a clip 11 and mounting bar 12 formed as an integral unit. The bar 12 has its end formed with oppositely disposed lugs 13 adapted to receive in abutting relation one end edge of a channel member 14, as will now be described.

The member 14 is of substantially channel formation and of a length slightly less than the distance from the bight portion 15 of the clip to the inner edges of the lugs 13 and of a width to

snugly bind upon the longitudinal edges of the mounting bar 12 when positioned thereupon. With the channel member 14 in position upon the bar 12, the open portion thereof is disposed in the direction of the clip 11, the longitudinal edges of the channel member extending slightly therebeyond, and these edges are turned inwardly to define flanges 16 for further securing of the bar 12 within the channel member. It should be noted that the one end of the channel member abuts the lugs 13 preventing possibility of end-

wise movement, endwise movement in the opposite direction being prevented by the bight portion 15 of the clip.

The channel member 14 is of a cross sectional area approximately twice that of the supporting bar 12 and when applied, the face plate 17 of the channel member will be spaced from the supporting bar 12, permitting insertion of anchorage members 18 endwise thereof.

The anchorage members 18 are identical in construction and are formed from a single blank of metal of a thickness slightly less than the space defined by the supporting bar 12 and the face plate 17, but is given a slight longitudinal curvature so as to effect a slight binding action against the abutting surfaces. The inner ends of the anchorage members are cut away as at 19 forming a lug 20 at the ends thereof and a shoulder 21 opposite thereto.

Preferably, the anchorage members are positioned within the channel member so that the cut away portion 19 is disposed downwardly, as clearly shown in Figures 4 and 7, and the edge plate 22, at suitably spaced points is provided with inwardly struck tongues 23, these tongues occupying a position so as to act upon the lug 20 and shoulder 21, thereby limiting extreme movements of the anchorage members. The outer or exposed ends of the members 18 are apertured to receive respective ends of a flexible chain or other member 24.

From the foregoing, it will be seen that an open-ended box-like structure is provided, the anchorage members 18 being slidably related to the holder, and either one or both may be adjusted laterally to accommodate cravats of differing widths, and in all instances, the symmetrical appearance of the holder will be maintained.

While I have shown and described a preferred embodiment of the invention, this is by way of illustration only, and I consider as my own, all such modifications in structure as fairly fall within the scope of the appended claims.

I claim:—

1. A cravat holder comprising an open-ended box-like structure including a clip member, laterally slidably members housed in respective ends of the box-like structure, each slidably member having a lug and a shoulder formed thereon, an inwardly disposed tongue at the ends of the box-like structure positioned between the lug and shoulder, whereby to limit sliding movements of the slidably members, and a flexible member having respective end portions fixed to respective ends of the slidably members.

2. A cravat holder comprising a mounting bar having a clip member, an open-ended channel member rigidly mounted thereon and extending substantially the full length of the bar, the channel member having a face plate lying parallel to the mounting bar and spaced therefrom, a laterally slid able member positioned in the open ends of the channel member, means cooperable between the channel member and respective slide members to limit the sliding movements thereof, and a flexible member having respective ends fixed to respective end portions of the slide members.
3. A cravat holder comprising a mounting bar having a clip member, an open-ended channel member disposed thereon and having flange

members bent to unite the two, the channel member having a face plate lying parallel to the mounting bar and spaced therefrom, a laterally slid able member positioned in the open ends of the channel member, said slide members having a curvature to effect a slight binding action between the mounting bar and the face plate, a tongue member formed adjacent the ends of the channel member and inwardly directed, a lug member and a shoulder formed on each slide member and cooperable with respective tongues to limit sliding movements thereof, and a flexible member having respective ends fixed to respective end portions of the slide members.
